ANIMATED WHISTLE

Mathew A. Strumor, Brooklyn, N. Y.

Application June 11, 1946, Serial No. 675,975

3 Claims. (Cl. 46—175)

1

This invention relates to toys or toy whistles or sound or noise makers, and the main object is the provision of a small device adapted to be blown into and so constructed that, with one end of the device constructed to simulate the head of an animal such as a wolf or other creature, or in any other suitable form, upon blowing into the device a sound will be given off, and simultaneously therewith the ears of the wolf's head will rise to a position of attention and the jaw will drop. The device might appropriately be termed a "wolf whistle," in the slang of the day, to be used by young men in hailing, or calling the attention of, young girls, such young men being popularly and jokingly often referred to as "wolves." Thus the invention presents a novel amusement device, which of course can serve as such for children as well as young men and women.

The above broad as well as additional and more specific objects will become apparent in the following description, wherein characters of reference refer to like-numbered parts in the accompanying drawing. It is to be noted that the drawing is intended solely for the purpose of illustration, and that it is neither desired nor intended to limit the scope of the invention to any or all of the features of construction shown excepting insofar as they may be deemed essential to the invention.

Referring briefly to the drawing,

Fig. 1 is a side elevational view of the toy or novelty.

Fig. 2 is a plan view of the same.

Fig. 3 is a cross-sectional view taken on the line 3—3 of Fig. 2.

Fig. 4 is a cross-sectional view taken on the line 4—4 of Fig. 2.

Referring in detail to the drawing, the numeral 10 indicates a tube or barrel having the reduced mouth end 11 and providing the continuous passage 12 through the device.

A member 13 is secured to the outer end of the barrel 10 and may be so shaped as to simulate the head of a wolf, as shown, or the head of any other creature, or any other desired simulation. As shown, the member 13 is formed of a continuous length of flat material, such as, for instance, sheet metal, so cut out that, when doubled back upon itself as shown in Fig. 2 it will form the two sides 14 which, in profile, simulate the head of a wolf. The above description and that to follow, in reference to the member or head 13, is to be taken as directed solely to the specific construction illustrated and

2

not as a limitation to the scope of the invention, as in practise the head of the device would preferably be a complete three-dimensional imitation of a wolf's head, with the top of the head 13 covered. The structure illustrated and herein described is in substantially simplified form to most clearly present the invention.

Pivottally mounted on a pin or pins 17 between the walls or jowls 16 of the head 13, through the media of turned down wings 15, is the lower jaw 18 of the head 13. The head 13 is secured to the end of the barrel 10 by means of flat connectors or arms 19, in any desired manner, such as, for instance, by soldering, or by having the arms 19 formed as integral extensions of the barrel and having their outer ends soldered to the jowls 16.

A flap 20 has its upper end 21 deformed rearward and its upper extremity 23 deformed or curved forward to provide a hook or catch. At the end 21 turned back extensions or wings 24 are pivottally mounted on a pin 22 supported in upstanding wings 25 rigid with the barrel 10. The flap 20 is adapted normally to lie against the open forward end of the barrel 10, and a wire spring 26, secured, as by solder, to one of the jowls 16, extends diagonally downward across and against the flap 20 to maintain the flap yieldably in closed position against the barrel end.

A pin 27 is pivottally supported at the top of the opposed sides 14 of the head, and has a crank 28 rigid therewith. This crank has one end of a rod 29 pivoted to the extremity thereof, at 30, the other end of the rod being pivoted to the jaw 18 at 31. A curved leaf spring 32 has its lower end secured to the jaw 18, as by solder, and extends upward in arched fashion, substantially as shown, with its upper end stopped by the leg 33 of an angle 34 secured, as by solder, to and between the jowls 16. An arm 35 is rigid, at its base, with the pin 27 at such an angle with respect to the crank 28 that, when the jaw 18 is in the closed position shown in Fig. 3 the end of the arm 35 registers under the catch 23. It is now apparent that, when the barrel 10 is blown into, the pressure of the breath will swing the flap upward on its pivot against the force of the spring 26, in a counterclockwise direction, Fig. 3, thereby releasing the arm 35 from engagement with the catch 23. Thus freed, the jaw 18 will be swung, in a clockwise direction, about its pivot 17, by the spring 32, into the open position shown in Figs. 1 and 3. The leg 36 of the angle 34 serves as a

limit stop to the clockwise movement of the crank 28 and hence also of the jaw 18.

Members 37, simulating in profile the ears of a wolf, are secured at their bases to the extremities of the pin 27 which extends through the sides 14 and has its ends peened against the ears 37 so that the ears are rigid with this pin and turn with it. Hence, as is obvious, as the jaw 18 opens in the manner described, the ears 37 will rise from the normal lowered position shown in full lines in Fig. 1 to the raised position shown in broken lines.

As a means of giving off a sound simultaneously with the action above described, upon blowing into the barrel 10 at the mouth end 11, a wind-operated diaphragm construction of standard type has been shown at 38. A well-shaped wall 39 is formed integrally with the barrel 10, near the end 11, with an opening upward therethrough communicating with the opening 12. A peripheral shoulder 40 is formed at the base of the wall 39, on which rests a ring 41 in which a diaphragm 42 is imbedded or mounted. A perforated cap 43 registers in the well 39 and frictionally engages the well wall while holding the diaphragm in place. As is well known with such sounding devices, blowing into the barrel 10 while accompanying the blowing with a hum, will set the diaphragm vibrating and cause it to give off a musical sound. If desired, of course, a suitable whistle might be substituted for the sounder 38.

Thus, blowing into the barrel as stated, will cause the musical sound to be given off and simultaneously will cause the mouth of the wolf's head to open and the ears to rise to attention. The ears and the jaw 18 are restored to their original position simply by either closing the jaw 18 or lowering the ears.

Obviously, modifications in form and structure may be made without departing from the spirit and scope of the invention.

I claim:

1. A device of the class described comprising a tubular housing having a passage therethrough, a rigid member mounted on said housing adjacent one end of said passage, a shaft transversely and pivotally mounted in said member and having ear-like members rigid on the ends thereof, a flap

valve pivotally suspended from the upper portion of said housing and normally positioned against said end of said passage to substantially close the same, the upper end of said valve having an upward extension, said extension being deformed to provide a friction catch, said shaft having a rod rigid therewith at right angles thereto, the extremity of said rod normally registering in said catch, said ears normally being positioned substantially parallel with the axis of said passage, resilient means urging said valve against said end of said passage, a tongue pivotally mounted at the rear end of the lower portion of said rigid member, a crank rigid with said shaft, a second rod having one end pivoted to said crank and the other end pivoted to said tongue, resilient means urging said tongue to swing away from said member, said tongue when said first rod registers in said catch as aforesaid being normally positioned substantially against said member, blowing into the other end of said passage causing said flap to swing outward from said first end of the passage and to release said first rod from said catch thereby enabling said last-named resilient means to swing said tongue away from said member thereby causing said second rod to turn said shaft through an arc to swing said ears upwardly to substantially right angles to said axis.

2. The device set forth in claim 1, said housing having a wind-actuated sound producer mounted thereon and in communication with said passage.

3. The device set forth in claim 1, said member having a limit stop limiting the arc of swing of said ears and said tongue upon said release of said first rod.

MATTHEW A. STRUMOR.
